Ms. 43

Pat. G. Abbott and Archibald Lawrence. 1852
Letter Patent No 431. Dated January 6th 1852.

The Schedule referred to in this Letter Patent and making part of the same.

To, all whom it may concern,

Be it known

that we James G. Abbott and Archibald Lawrence of the City and
County of Philadelphia, and State of Pennsylvania have invented or pro-
duced a new and original design for the external decoration of a stove
called, "

the Liberty, Air tight Cook"

and we do hereby declare that the following is a full and exact descrip-
tion of the same.

Fig 1 is a side elevation

Fig 2 is a front view of one of the legs.

D

Des. 431

A Is the side plate of the Stove

B Is the edge of the top plate

C Is the bottom plate

D Is the ornamental device on the oven door.

E Represents the ornament on the side door of the fire chamber

F Represents the design and configuration of the leg and the ornament thereon

Having described and represented my new design of stove plates for the Liberty Air-tight back Stove.

What we claim as new and of our invention and desire to secure by
Letter Patent is the design or ornament, shape and configuration of stove plates
as represented in the annexed drawings at D, E, F, figs 1, 2, 3, 4.

In testimony whereof we have hereunto signed our names
before two subscribing witnesses.
